UNITED STATES PATENT OFFICE.

HENRY A. WEIHMANN, OF PHILADELPHIA, PENNSYLVANIA, ASSIGNOR TO
SIMONS, BROTHER & CO., OF SAME PLACE.

DESIGN FOR A CANE OR UMBRELLA HANDLE.

SPECIFICATION forming part of Design No. 19,995, dated July 1, 1890.

Application filed April 15, 1890. Serial No. 348,088. Term of patent 3½ years.

To all whom it may concern:

Be it known that I, HENRY A. WEIHMANN, a citizen of the United States, residing in Philadelphia, in the county of Philadelphia and State of Pennsylvania, have invented and produced a new and original Design for Cane or Umbrella Handles, of which the following is a specification, reference being had to the accompanying drawings, forming part thereof.

10 In said drawings, Figures 1 and 2 are side elevations of the umbrella or cane handle, looking at the same from two points of observation arranged at substantially right angles to each other.

15 The handle is made of any suitable material. It consists of the body part A, the head B, and the base part C. The body part A swells out at both top and bottom with an intermediate recessed portion, and is formed with 20 vertical bars D and E, arranged alternately, of which D are plain, while E are highly ornamented. The desired shape of the parts D and E is excellently shown in the drawings. The head B continues as a slightly rounded 25 portion of the top of the body part and unites

with the body part through the mediation of a band G, with upwardly-extending points and slightly depressed and shaded. The upper part of the head B is plain. The base part C consists of a swelled portion at the top 30 and a depressed portion at the bottom, said parts being separated from the body part A at the top by an annular band or rim H and mounted at the bottom with a similar band or rim I. The base portion C is made up of 35 vertical parts J of smooth or plain work and K of ornamented work, and these parts J are arranged under the parts D, and the parts K under the parts E, substantially as shown.

Having now described my new design, what 40 I claim as new, and desire to secure by Letters Patent, is—

The design for an umbrella or cane handle, substantially as herein described and shown.

In testimony of which invention I have 45 hereunto set my hand.

HENRY A. WEIHMANN.
